DRY ORE CONCENTRATOR

Filed May 31, 1946

FIG. 1.

FIG. 2.

FIG. 3.

FIG. 4.

FIG. 5. FIG. 6. FIG. 7.

FRANK J. MATHEWS,
INVENTOR

BY ATTORNEY.

Prepared ore is fed to the conveyor 1 from an open-topped feed trough 35 mounted upon the frame 14 superjacent to the upper run of the conveyor and extending across said run in a substantially horizontal direction, said trough having an ore receiving end portion which projects from the right side of the conveyor as viewed in Fig. 1. This trough is arcuate as viewed in cross section and it is mounted in a slightly tilted position (see Fig. 2) so that the side thereof which is nearest to the upper end of the conveyor is considerably lower than the opposite side of the trough. Also the trough progressively narrows as it extends across the conveyor (see Fig. 3) toward the side of the conveyor farthest from the ore receiving end of the trough.

A spiral ore feeding blade 36, fixed to a supplementary driving shaft 37, is mounted interiorly of said trough in a position to advance the ore along the trough after it has been fed into the already mentioned projecting end portion of the trough, the advancing ore progressively discharging over the edge of the trough. Said spiral blade tapers from end to end in a manner corresponding to the taper of the trough. Said shaft 37 has fixed to it a pulley 70 which is driven by a belt 71.

Ore is fed to the wide end of the tapered trough from a conical hopper 38 rotatably supported upon a conical ball bearing structure 38a which surrounds the lower end portion of said hopper, said bearing structure being supported by a frame cross piece 39. Said hopper has a tubular downward outlet extension 40 positioned over the receiving end portion of the trough 35, the diameter of said extension being slightly reduced at 41 where it is surrounded by a lower ball bearing 42 sustained by a standard 43 mounted upon the aforesaid transverse frame member 13.

An ore-sorting device is mounted within the mouth portion of the hopper 38, this device comprising a horizontal disk 44 having an upwardly projecting central conical hub 45. Said disk 44 is shown furnished with four equally spaced apart peripheral attaching arms 46 which are down-curved into and attached to the mouth portion of the hopper, their upper ends being attached to said disk. Upon the upper face of said disk are mounted a plurality of curved fins 44b which radiate from the lower end of the hub 45 and are circumferentially spaced apart as shown in Fig. 3.

Ore is fed to the hopper from a suitable supply (not shown), through a vertical tube 47 extending through guide means 49 supported upon the upper frame piece 48. The lower end of said tube 47 has a frusto-conical expansion 50 concentric to the already mentioned conical hub 45, there being an ore feeding clearance between these two conical parts. As the fed ore is deposited upon the spaced apart fins 44b, carried by the rotating disk 44, the larger pieces of ore are caused to be centrifuged away from the hopper and fall onto any suitable receiving means (not shown) provided for them while the finer material drops down through the annular space 44c between the disk 44 and the mouth of the hopper 38.

During the operation of the machine the hopper 38 is continuously rotated in the direction indicated by the arrow in Fig. 3 by means of a pulley 52 turned by the driving belt 53 driven by any suitable means (not shown). A spacing sleeve 54 is placed around the tube 47 between said pulley and the bearing 42. At the power supply end of the main driving means is a pulley 55 driven by a belt 56, said pulley 55 being secured to one end

portion of a driving shaft 57 rotatably supported by the main frame 14. Said shaft 57 carries two pinions 58 which mesh with the driving gears 59 secured to the already mentioned shaft 26 of the pawl-operating assemblies 21a and 21b.

The aforesaid pawl 21 advances the ratchet wheels 23 in a step-by-step fashion thus rotating the shaft 8s and in turn the upper roller 8 of the endless conveyor.

10 The conveyor rollers or drums 8 and 9 are both furnished near their ends with radially projecting pins 63 so spaced apart as to act properly upon the projecting end portions of the conveyor riffle-slats 41, thus to cause a positive advance of 15 the riffle-carrying canvas 10 of the endless conveyor 1.

Between adjacent riffles along each side edge portion of the canvas belt 10 are rubber strips 113 which are angular in cross section, one of their flanges being secured to the belt and their other flanges normally projecting away from the face of the belt to hem in the conveyed ore. As these rubber strips pass over the rollers their last mentioned flanges are deflected inwardly so as to accommodate the curvature at that time produced in the attached flanges.

In the operation of the device, most of the work will be done with the endless conveyor adjusted to a forty-five degree angle, but some work can be done with said conveyor at a less angle. The canvas portion of said conveyor should be advanced one-half of an inch at a time by the pawl 21. The movement is very sudden, not cam-like. By this movement all the material on the upper run of the endless conveyor is loosened up and as it settles back again the concentrates will work down to the canvas adjacent to the upper edges of the ascending slats and will be carried past the place of feed up over the upper roller and then it will drop into a chute or receptacle provided to receive them. And as a fresh supply of the material is continually falling onto the upper portion of the upper canvas run it begins to fall from one slat to the next one below until the concentrates work down and accumulate to the upper edges of the ascending slats, crowding the lighter materials up over the slats, so that only the concentrates remain adjacent the upper sides of the slats to be carried up over the top roller, while the lighter materials keep falling downwardly from one slat to another until they reach the lower end of the endless conveyor and are thence carried to the tailing dump.

The foregoing concentrating operation would be very slow were it not for the sorting methods before the material reaches the concentrator. First, two-thirds of the material is eliminated at a trommel screen. Then the remaining portion is put through a dry classifier which removes all sizes that do not carry values, and the remainder of not over thirty to ten per cent of the original bulk is all that is delivered to the concentrator.

I claim:

1. In a dry ore concentrator, a main frame, a belt type inclined endless conveyor mounted thereon and provided with riffle strips and comprising an upper and a lower belt supporting roller and a conveyor frame upon which said rollers are mounted to turn about substantially horizontal axes, an open-topped feed trough mounted upon said main frame superjacent to the upper part of the upper run of said conveyor, and extending in a substantially horizontal direction and having a receiving end portion projecting beyond one side of said conveyor, said trough

diminishing in depth from its said feed end portion to a point adjacent to its opposite end, means to feed prepared ore into said projecting end portion of said trough, a feeding spiral extending internally along said trough, means to rotate said spiral in a direction to feed the ore to the conveyor, and mechanical means connected with said conveyor to drive it in an intermittent manner in a direction to advance its upper run in an upward direction, said feed trough having an arcuate cross section which tapers away from the ore-receiving end of the trough, said feeding spiral tapering in correspondence with the taper of said trough.

2. In an ore concentrator of the kind described, a support, an endless inclined conveyor supported thereon, said conveyor comprising an endless belt portion and rollers over which it passes, transversely extending riffles carried by said belt spaced apart lengthwise thereof, said riffles having end portions projecting beyond each side of the belt and at least one of said rollers having radially extending pins positioned to engage said projecting end portions of said riffles thereby to advance said belt portion.

FRANK J. MATHEWS.
